UNITED STATES PATENT OFFICE.

ANDRZEJ BIGOS, OF LORAIN, OHIO.

SHOE-CLASP.

1,296,157.

Specification of Letters Patent.

Patented Mar. 4, 1919.

Application filed September 23, 1918. Serial No. 255,292.

To all whom it may concern:

Be it known that I, ANDRZEJ BIGOS, a citizen of the United States of America, residing at Lorain, in the county of Lorain and

5 State of Ohio, have invented certain new and useful Improvements in Shoe-Clasps, of which the following is a specification.

The primary object of the invention is the provision of a simple and inexpensive 10 clasp especially designed for shoes for retaining the shoe closed upon the foot of the wearer without the employment of the usual form of buttons or laces.

A further object of the invention is the provision of means adapted for taking the place of the ordinary buttons and button holes employed upon shoes and whereby the opening flaps of a shoe may be readily secured together with great strength and easily 20 released whenever desired.

A still further object of the invention is the provision of a clasp adapted to be readily secured to the eyelets of a laced shoe whereby the shoe is converted into a form 25 of buttoned shoe readily opened and closed when the occasion requires.

With these general objects in view the device consists of the novel combination and arrangement of parts hereinafter fully described and illustrated in the accompanying drawing in which like reference characters designate corresponding parts throughout the several views.

In the drawings,

35 Fig. 1 is a perspective view of a shoe provided with my invention;

Fig. 2 is an enlarged elevational view of a front portion thereof with parts broken away;

40 Fig. 3 is a transverse sectional view taken upon line III—III of Fig. 2;

Fig. 4 is a perspective view of the latch portion of the clasp detached;

Fig. 5 is a sectional view through one of 45 the eyelets of the body flap when the shoe is closed, taken upon line V—V of Fig. 2;

Fig. 6 is a plan view illustrating a modified form of clamp;

Fig. 7 is a transverse sectional view taken 50 upon line VII—VII of Fig. 6;

Fig. 8 is a front elevation of another form of my clamp; and

Fig. 9 is a transverse sectional view thereof taken upon line IX—IX of Fig. 8.

For convenience in illustrating the operation of my clasp, a shoe 10 is shown having the side flaps 11 and 12 of the shoe upper provided with a plurality of the clasps for detachably connecting the flaps together.

Suitable eyelets 13 and 14 are provided 60 at opposite points in the flaps 11 and 12 adjacent the edges thereof positioned in pairs above one another at the front of the shoe. These eyelets may be mounted upon the flaps during the manufacture of the 65 shoe, but it will be understood that the usual eyelets of a laced shoe will serve the purpose equally as well.

A latch or bar 15 is provided for each 70 pair of eyelets preferably attached to the eyelets upon one of the flaps, such as 12, by means of screws 16 extending through perforations 17 adjacent one end of the latch bars and threaded into button shaped heads 18 at the exposed outer face of the carried 75 flap 12. An abutment or shoulder 19 is transversely carried by each bar 15 adapted for engaging the adjacent edge of the flap when the bar is mounted thereon while the head 18 of the retaining screw 16 of each 80 bar 15 is adapted to seat upon the top of the shoulder 19 of its respective bar. In this manner, a latch bar 15 will be provided for each pair of eyelets possessed by the 85 shoe and while the bars are preferably secured in the manner noted to one of the flaps 11 and 12, the latch bars 15 may be fixedly secured by the screws 16 in alternation with the flaps 11 and 12.

A post 20 is provided upon each bar 15 90 adjacent the opposite end thereof from its perforation 17 and adapted for insertion through the adjacently positioned eyelet of the opposite flap such as the eyelet 13 of the flap 11. A locking plate 21 similar in appearance to the heads 18, is swingingly mounted upon each bar 15 by means of a pivot pin 22 carried by the plate and headed through an opening 23 provided in the bar 15. A spacing sleeve 24 is provided upon 95

100

each pin 22 between the bar 15 and its plate 21, the said sleeve and pin being positioned outwardly of the edge of the flap 11 when the flap is secured by the clasp with the post 20 extending through the eyelet 13 thereof.

A cam flange 25 depends from the plate 21 at the diametrically opposite side thereof from pin 22 adapted for wedging engagement within an annular groove 26 of the post 20 carried by the latch bar 15 upon which the plate is pivoted. With one of my clasps secured within each eyelet 14 of the flap 12, the shoe 10 will be ready for use in wearing by a person and upon swinging the plates 21 inwardly toward the heads 18, the opposite eyelets 13 may be readily mounted or buttoned upon the posts 20 and the plates 21 revolved for wedging the flanges 25 within the grooves 26 and locking the plates to the posts 20. By reversing the operation, the clasps are readily released for removing the eyelets 13 from the posts 20 while the flaps 11 and 12 are secured together by great strength when the clasps are locked as hereinbefore described.

A modified form of construction is illustrated in Figs. 6 and 7 of the drawing substantially identical in operation to that heretofore described but in which the latch bar 15' is secured to one flap, such as 12', of a shoe by means of a screw 16' positioned through the eyelet 14' of the flap. A cam plate 21' has an integral sleeve 24' into which a screw 22' is threaded which passes through the bar 15'. The grooved post 20' upon the bar 15' is received through the eyelet 13' of the opposite flap 11' for engagement by the cam or wedging flange 25' of the plate 21'.

The appearance presented by the preferred form of my invention is pleasing and shows a plurality of sets or pairs of button members consisting of the heads 18 and plates 21, while in the modified form of the device a single row of the button-shaped plates 21' appear at one side only of the shoe opening. Both forms of the invention possess great strength for retaining the shoe closed and are simple in construction having interchangeable parts readily replaced when required.

In the form of the device illustrated in Figs. 8 and 9 of the drawing, the opposite sides 30 and 31 of the shoe upper or flaps are adapted to overlap with a button-hole 32 provided in the overlapping flap 30. A clasp is secured to the flap 31 in the form of a plate 33 attached to the flap by means of a rivet 34 and having an upright post 35 at one side thereof upon which a circular disk 36 is pivoted. A notched lug 37 upon the opposite side of the plate 33 is adapted to extend through the button-hole 32, and to

be engaged by a depending cam flange 38 65 at the free edge of the disk 36. In this manner, the clasp is securely seated upon one of the flaps for locking engagement with the adjacent portion of the opposite flap.

What I claim as new is:

1. A shoe clasp comprising a latch bar, means adapted for attaching one end of the bar adjacent the edge of a shoe flap, a post adjacent the other end of the bar adapted for insertion through the opposite flap of a 75 shoe, and a cam plate pivoted upon the bar adapted for locking engagement with the said post.

2. A shoe clasp comprising a latch bar adapted to be secured through an eyelet of 80 one of the flaps of a shoe, a post upon said bar adapted to receive thereon an eyelet of the other flap of the shoe, and a plate pivoted upon said bar having a depending cam flange adapted for locking engagement with 85 said post when the clasp is closed.

3. A shoe clasp comprising a latch bar for a pair of eyelets on the flaps of a shoe, a button-shaped head adapted to overlie one eyelet of the pair of eyelets and to be secured therethrough to the adjacent bar, a post upon the bar adapted for receiving thereon the other eyelet, and a plate pivoted upon the bar having a cam flange adapted for wedging engagement with the post of 95 the bar when the clasp is in its closed operative position.

4. A shoe clasp comprising a latch bar for a pair of eyelets on the flaps of a shoe and adapted to be positioned beneath said flaps, a screw extending through the bar and adapted to extend through one eyelet of one shoe flap, a button-shaped head threaded upon the outer end of the screw, a transverse shoulder upon the bar inwardly of the adjacent screw and adapted to be positioned inwardly of the adjacent edge of said one shoe flap with the adjacent head seated upon said shoulder, an upright post carried by the bar adapted to project through the other eyelet of the pair of eyelets when the device is closed, and a button-shaped plate pivoted upon the bar adapted for wedging engagement with the post thereof when in its operative closed position.

5. A shoe clasp comprising a latch bar for a pair of eyelets on the flaps of a shoe and adapted to be positioned beneath said flaps, a screw extending through the bar and adapted to extend through one eyelet of one shoe flap, a button-shaped head threaded upon the outer end of the screw, a transverse shoulder upon the bar inwardly of the adjacent screw and adapted to be positioned inwardly of the adjacent edge of said one shoe flap with the adjacent head seated upon said shoulder, an upright post carried by the bar adapted to project through the other

eyelet of the pair of eyelets when the device is closed, a button-shaped plate for the bar, a pin adjacent one edge of the plate pivoted to the bar thereof, a sleeve upon the pin between the bar and plate, the post being provided with an annular groove, and a depending cam flange upon the plate adapted

for wedging engagement within the groove of the post when the clasp is closed to operatively connect the opposite flaps of the 10 shoe.

In testimony whereof I affix my signature.

ANDRZEJ BIGOS.
